UNITED STATES PATENT OFFICE.

JOHN WOLKOFF, OF EAST ORANGE, NEW JERSEY.

ELECTRIC MOTOR.

Application filed January 20, 1923. Serial No. 614,017.

An object of this invention is to provide centrally to the supporting frame 1 and extending centrally into the armature chamber is an annular core 5, said core being permanently and rigidly connected to the frame 60 1 by screw bolts 6. Around the core 5 is arranged a large coil 7, said coil being connected to the line or source of supply and to a contact bar, as will be fully hereinafter described. Secured centrally to the supporting 65 frame and to the inner end of the core 5 are bearings 8 for the armature shaft 9. The outer end of the armature shaft is provided with a belt wheel 10 and the inner end thereof carries the usual commutator bars 11. 70 Rigidly keyed to the armature shaft is an annular frame 12 which, by means of bolts 13, support the armature 14. The armature is of the ordinary ring type, series wound. The coils 16 of the armature are connected to 75 the commutator bars through the radiating rods 15, as clearly shown in Figs. 1 and 4.

Another object of the invention is to provide a simple and improved yieldable holder for the commutator brushes, said holder being 16 rotatively adjustable for the purpose of reversing the rotation of the commutator; varying the speed of the armature and bringing said armature to a stop. This latter result is obtained by placing the brushes in a neutral or central position with respect to 18 the field magnets and the magnetic lines of force flowing between said magnets.

Another object of the invention is to provide a simple means for reducing the speed of the motor by cutting out two of the 20 brushes and their contact bars.

There are other important objects and advantages of the invention which will appear hereinafter, and which will be apparent to one skilled in the art.

25 In the drawings, Figure 1 is a vertical longitudinal sectional view through the motor;

Fig. 2 a detail vertical sectional view of a portion of the brush holder;

30 Fig. 3 a perspective view of the brush holder detached;

Fig. 4 a vertical sectional view substantially on the line 4-4 of Fig. 1, portions of the inner frame being broken away to more 35 clearly show the construction;

Fig. 5 an elevation of the inner face of the brush holder showing the contact bars on which the brush holders slide and with which they make electrical contact;

40 Fig. 6 a detail cross sectional view of a portion of the device for cutting out two of the commutator brushes;

Fig. 7 a detail elevation of the rotary bridge bar for cutting in and cutting out two 45 of the brushes;

Fig. 8 a diagrammatic view of the motor and its connections; and

Fig. 9 a view similar to Fig. 8 showing two of the brushes cut out.

50 Referring to the various parts by numerals, 1 designates the supporting frame formed of cast iron and provided with a supporting base 2. This frame is formed with two large pole pieces 3, arranged at 55 diametrically opposite points and extending inwardly in the same direction. Secured

95 The frame 12 and the entire inner side of the supporting frame 1 is enclosed within a frame or casing 18. Mounted in the vertical side wall of the casing 18, and axially in line with the inner end of the armature shaft is a tubular stub shaft 19, a portion 100 of said shaft extending within the casing and a portion thereof extending outside of the casing. On the exterior portion of the said stub shaft is rigidly secured a knob or finger piece 20 by means of which the stub shaft may be rotated in either direction. The inner end of the armature shaft extends 105 into the stub shaft 19 whereby said stub shaft will serve as a bearing for one end of the armature shaft. Rigidly secured to the inner end of the stub shaft, close to the 110 inner side of the casing 18, is a plate 21.

BEST AVAILABLE COPY

Secured to said plate at diametrically opposite points are four radially arranged flat or leaf springs 22. To the outer end of each of said springs 22 is secured an inwardly extending comparatively thin block 23 of insulating material. Secured to the inner end of each of these blocks 23 is a radially arranged brush holder 24. These brush holders are rectangular and tubular and mounted in each one is a brush block 25. The brush holders are radially arranged and the inner faces of the brush blocks bear directly on the commutator bars. There are four of these brushes 25 and they are arranged to engage the commutator bars at diametrically opposite points, as clearly shown in Fig. 4. Each brush block is yieldingly forced inwardly to engage the commutator by a spring 26, one end of said spring 20 being connected to the outer end of the brush and the other end of said spring being connected to the brush holder. It is manifest that by rotating the finger piece or knob 20 in either direction the brushes will be rotatively adjusted around the commutator.

Within the casing 18 is mounted a ring 27 of insulating material the inner face of said ring being adjacent to the outer sides of the brush holders. Mounted in the insulating ring 27 are four segmental contact bars 28+, 28+ and 28-, 28-. Each contact bar is arranged to be engaged, and in electrical contact with the outer portion of a brush holder. The spring 22 yieldingly holds the brush holders in engagement with the contact bars, as clearly shown in Figs. 1 and 2. To prevent the brush holders from being moved to their respective contact bars the plate 21 is provided with a stop pin 29 which enters and travels in a segmental slot 30 formed in the rigid casing 18, said slotted pin limiting the oscillation or rotation of the plate 21 and the brush holders. The slot 30 is of sufficient length to permit the brush holders to be moved from one end of the contact bars to the other end thereof, but will prevent the brush holders being moved off their proper bars and into engagement with the adjacent contact bar in either direction.

The contact bars 28 are concentrically arranged and are spaced to coincide with the radial arrangement of the four field poles. This arrangement is diagrammatically illustrated in Fig. 8. The brush holders are similarly arranged, as shown in Fig. 4; and diagrammatically in Fig. 8.

To the exterior of the enclosed casing 18, and directly below the commutator and brush holders, is secured a block 31 of insulating material. On this block are secured spring contact plates, a, b, c, d, e and f. These contact plates are electrically connected to the source of supply or line wires and to the four brush bars, as will be here-

inafter pointed out. Mounted in suitable bearings, and directly in front of the bar 31, is a rotary cut out switch 32. This switch consists of a horizontal shaft 33 carrying a cylinder 34 of insulating material. Embedded in said cylinder are four bridge bars 35 and 35'; 36 and 36'. The bridge bars 35 and 35' are short and are so placed in the cylinder 34 that they may be brought into engagement with the contact plates a and b, and d and e respectively. The bridge bars 36 and 36' are longer than the bars 35 and are so arranged in the cylinder 34 that the bar 36 may be brought into engagement with the contacts a, b and c and the bar 36' into engagement with contact bars d, e and f. The cylinder 34 may be rotated by finger pieces 37 secured to the end of the shaft 33. The bridge bars are so arranged in the cylinder 34 that all of the contacts a to f inclusive may be disconnected from each other in order to cut off all current from the motor and thereby render it inoperative. Secured to the shaft 33 is a hexagonal stop plate 38 which is adapted to be engaged by two spring holding arms 39 diametrically arranged and adapted to engage diametrically arranged faces on the plate 38. By this arrangement the cylinder 34 may be readily stopped in three positions; one of those positions will bring the bridge bars 35 and 35' into engagement with their contact bars; another position will bring the bridge bars 36 and 36' into engagement with their contact bars, and the third position will bring the plain surface of the insulating cylinder 34 into engagement with the contact bars and thereby cut all current from the motor.

In Figure 8 the motor is represented diagrammatically. The + side of the line is connected directly to the field coil 7 and from there is led by connection 40 to contact a. As shown in this figure the bridge bars 36 and 36' are in engagement with the contact bars. The field coil contact a is connected through bridge 36 to the contact bars b and c and these bars are electrically connected by wires 41 and 42 to the two brush contact bars 28+, which are complementary to the upper and lower + field poles. The - side of the line is connected to contact bar d and this contact bar is connected through the bridge bar 36 to the contact bars e and f. These latter bars are electrically connected by wires 43 and 44 to the two brush bars 28-. These brush bars are arranged on the right and left hand sides of the brush bars 28+ and are complementary with the - field poles. As illustrated in Fig. 8 the brushes are arranged centrally or midway between the ends of their contact bars and are consequently centrally located with respect to the field poles. This is the neutral position of the brushes and

the result of this neutral position is that the pull on the armature tending to rotate it is equal in opposite directions and the armature will not rotate. By rotating the brush 5 holders clock-wise the balanced condition of the armature will be upset and the pull tending to rotate the armature clock-wise will dominate and the armature will be turned in that direction. The nearer the brush holders are brought, clock-wise, to the ends of their contact bars the greater will be the speed of the armature. In order to reverse 10 the direction of rotation of the armature the brush holders must be turned anti-clock-wise beyond the central or neutral position. The speed of the armature may be varied by varying the distance of the brush holders from the middle or neutral position to either end of the contact bar.

15 20 If it be desired to reduce the speed and the power of the motor the switch 32 is rotated to bring the bridge bars 35 and 35' into engagement with the contact bars *a* and *b*, and *d* and *e*, as illustrated in Fig. 9 of the drawings. This cuts out one brush contact bar 28+ and one contact bar 28-. This will reduce the speed of the armature and likewise reduce the power thereof.

The form of motor shown in the drawings 25 and described herein, but not claimed, will be claimed in a divisional application.

What I claim is:

1. An electric motor comprising field poles, an armature shaft, an armature sup-

ported on said shaft, a commutator on the 35 armature shaft, brush holders, a brush mounted in each holder and adapted to engage the armature, a segmental contact bar for each brush holder, each contact bar being arranged complementary to a field pole 40 piece, means for rotatively mounting the brush holders to permit them to be simultaneously adjusted along the contact bars whereby the relation of each brush holder to its complementary pole piece may be varied, 45 and means for yieldingly supporting the brush holders on their rotating means, said yielding supporting means pressing the brush holders against the contact bars.

2. An electric motor comprising field 50 poles, an armature shaft, an armature supported on said shaft, a commutator on the armature shaft, brush holders, a brush mounted in each holder and adapted to engage the armature, a fixed segmental contact bar for each brush holder, a rotatable plate concentric with the armature shaft, radially arranged spring arms carried by said plate, said radial arms carrying the brush 55 holders on their outer ends and yieldingly pressing said holders against the contact bars, and spring means connected to the brushes and to the brush holders to yieldingly press the brushes against the commutator.

In testimony whereof I hereunto affix my signature.

JOHN WOLKOFF.
